UNITED STATES PATENT OFFICE

2,542,411

CIRCUIT BREAKER

William O. Henschke, Longmeadow, Mass., assignor to American Bosch Corporation, Springfield, Mass., a corporation of New York

Application May 8, 1946, Serial No. 668,071

5 Claims. (Cl. 200—30)

1 This invention relates to electrical circuit interrupters or breakers of the type used for making and breaking an electric circuit in the ignition system of an internal combustion engine and has particular reference to the provision of a new and improved interrupter or breaker of the pivotless type.

An object of the invention is to provide an interrupter or breaker of the type set forth wherein the sliding motion between the cam follower and the contact carrying lever is substantially reduced or eliminated thereby substantially reducing or eliminating the lubrication requirements at this point which lubrication has been the source of considerable difficulty and trouble in prior constructions.

Another object of the invention is to provide a device of the type set forth which is relatively simple and economical to manufacture yet efficient in operation and in which means is provided for giving greatest strength or reinforcement at the point where it is most needed on the levers and also for controlling the cantilever action of the cam follower lever and tending to retain the cam follower block in a radial line with the cam yet being so arranged that the levers can each be made of a single piece of material.

Another object of the invention is to provide a mounting for a device of the character set forth on its mounting block or support which tends to reduce contact bounce upon the closure of the contacts.

Another object of the invention is to provide a construction of the type set forth wherein a single combined pivot and fastener may be employed whereby the cam follower may be adjusted in a line radial to the cam and which also tends to reduce contact bounce as set forth above.

Other objects and advantages of the invention will be apparent from the following description taken in connection with the accompanying drawings. It will be understood that some changes may be made in the details of construction and arrangement of parts as the preferred form of the invention has been shown by way of illustration only.

Referring to the drawings:

Fig. 1 is a top or plan view of an interrupter or breaker constructed according to the invention;

Fig. 2 is a view similar to Fig. 1 but showing a different cam follower arrangement;

Fig. 3 is a fragmentary side view taken along lines 3—3 of Fig. 1 looking in the direction of the arrows;

2 Fig. 4 is a sectional view, on an enlarged scale, taken on line 4—4 of Fig. 1, looking in the direction of the arrows;

Fig. 5 is a sectional view, on an enlarged scale, taken on line 5—5 of Fig. 1, looking in the direction of the arrows; and

Fig. 6 is a fragmentary sectional view taken on line 6—6 of Fig. 1, looking in the direction of the arrows.

10 Referring more particularly to the drawings wherein similar reference characters designate corresponding parts throughout the several views, the device shown embodying the invention in Fig. 1 comprises the breaker plate or supporting member 1 of the usual type, on which is mounted the interrupter or breaker bracket 2.

The breaker is mounted on the support or bracket 2 which is secured to the supporting member 1 by only a single solid fastening which, 20 as shown, is the screw 3 extending through the pivot 4 for the support 2, and then screwed into the plate 1. The rivet 5 having the slotted eccentric head 6 is positioned in a slot 7 in the support 2 and facilitates adjustment of the support 2 relative to the contact opening cam 8.

On the support 2 is the upturned flange 9 carrying the stationary contact 10.

Adjacent the opposite end of the support 2 is another upturned flange 11 having an opening through which extends the bolt 12 which is insulated from the flange 11 by the insulating washers 13 and 14. Also mounted on the bolt 12 are the flexible levers or cantilevers 15 and 16 which are insulated from the flange 11 by the block 14 of insulating material and from the terminal 18 by the insulator 19. The lock washer 20 and nut 21 serve to retain the parts in assembled relation on the flange 11 and bolt 12.

The cantilever 16 carries the second contact 22 which is normally in engagement with the first contact 10 due to the resiliency of the cantilever 16. The said cantilever 16 is preferably made by forming from a single piece of material and has the integral marginal flanges 23 along its sides for greater reinforcement and strength. The greatest width of flange or reinforcement 23 is provided at substantially the point where the cantilever 16 is engaged by the cam follower block 24 for separating the contact 22 from the contact 10 and the flanges 23 taper in each direction from that point thus giving greatest strength at the point it is most needed and yet not materially detracting from the resiliency of the cantilever 16 nor unduly adding weight thereto.

The cantilever 15 has the cam follower block 24 secured by rivets or other suitable means to

its end opposite the end of the cantilever which is connected to the bolt 12. This cantilever 15 may be provided with the central rib or reinforcement 25, see Fig. 5, which extends from the block 24 a desired distance toward the connection of the opposite end of the cantilever 19 with the bolt 12. Because of this rib or reinforcement 25, the cantilever 15 tends to retain the cam follower block 24 in a radial line with the cam 8 and this reinforcement 25 also allows a more accurate control of the spring or cantilever arm 15 thus allowing the arm to bend only where desired, that is, near the point of its being secured to the bolt 12 thus insuring control of the direction of movement of the block 24 and because of this and also because both levers 15 and 16 turn on substantially a common center any relative sliding motion between the follower block 24 and contact carrying lever 16 is either eliminated or substantially reduced which in turn eliminates or substantially reduces the lubrication requirements at this point.

In the construction shown in Fig. 1 the lever 15 is so positioned as to resiliently urge the block 24 in engagement with the periphery of the cam at all times whereas in the construction shown in Fig. 2, this lever 15 is so positioned as to urge the block 24 in engagement with the lever 16 at all times and only engages the cam when the contacts are to be separated.

Another feature of the present invention is that because the block 24 is positioned between the bolt 12 and contacts 10 and 22 the cam lift of the lever 16 will be even greater than the motion of the lever 16 at the point of engagement with the follower block 24.

It is particularly pointed out that due to the fact that the bracket 2 is fastened to the supporting member 1 by the single solid fastening 2 and at one point only, that this construction will tend to reduce contact bounce on closure of the contacts because of the damping action between the unsecured portion of the contact bracket or support 2 and the base or supporting member 1 on which it is mounted.

From the foregoing it will be seen that I have provided simple, efficient and economical means for obtaining all of the objects and advantages of the invention.

Having described my invention, I claim:

1. In an electric circuit breaker mechanism for internal combustion engines, a bracket, a pair of make and break contacts in alignment with each other and normally in contact with each other, one of said contacts being secured to said bracket, means whereby said bracket may be adjusted as a unit to allow the adjustment of said mechanism without altering the relation of the contacts, a cam follower block, a leaf spring supporting said follower block, a second leaf spring supporting the other of said contacts and adapted to be engaged by said follower block to separate said contacts, said leaf springs having end portions secured to said bracket in substantially adjacent relation and being adapted to turn about a substantially common center and thereby reduce relative sliding motion between the follower block and contact supporting leaf spring when the block engages the leaf spring to separate the contacts.

2. In an electric circuit breaker mechanism

for internal combustion engines, a bracket, a pair of make and break contacts normally in fixed alignment with each other, a leaf spring supporting one of said contacts for movement relative to the other of said contacts, one of said contacts being secured to said bracket, means whereby said bracket may be adjusted as a unit to allow adjustment of said mechanism without altering the relation of the contacts, a cam follower, a second leaf spring supporting said follower, said leaf springs being secured to said support in substantially adjacent relation, said follower being adapted to engage said contact supporting leaf spring to cause relative movement of the contacts, said contact supporting leaf spring having reinforcing means with the point of greatest strength at substantially the location where said follower engages said leaf spring.

3. In an electric circuit breaker mechanism for internal combustion engines, a pair of make and break contacts, a leaf spring supporting one of said contacts for movement relative to the other of said contacts, a cam follower, a second leaf spring supporting said follower, said follower being adapted to engage said contact supporting leaf spring to cause relative movement of the contacts, said leaf springs being secured to said support in substantially adjacent relation, said contact supporting leaf spring having reinforcing means with the point of greatest strength at substantially the location where said follower engages said leaf spring and said reinforcing tapering in both directions therefrom.

4. In an electric circuit breaker mechanism for internal combustion engines, a pair of make and break contacts, a leaf spring supporting one of said contacts for movement relative to the other of said contacts, a cam follower adapted to cause movement of said contact supporting leaf spring, said leaf springs being secured to said support in substantially adjacent relation, said contact supporting leaf spring having flanged reinforcing means with the greatest reinforcing strength located substantially at the point where said cam follower is adapted to engage said leaf spring.

5. In an electric circuit breaker mechanism for internal combustion engines, a pair of make and break contacts, a leaf spring supporting one of said contacts for movement relative to the other of said contacts, a cam follower adapted to cause movement of said contact supporting leaf spring, said leaf springs being secured to said support in substantially adjacent relation, said contact supporting leaf spring having flanged reinforcing means with the greatest reinforcing strength located substantially at the center of said contact supporting leaf spring.

WILLIAM O. HENSCHKE.
